UNITED STATES PATENT OFFICE.

ARTHUR PURDON, OF WILKINSBURG, PENNSYLVANIA, ASSIGNOR TO WESTINGHOUSE ELECTRIC AND MANUFACTURING COMPANY, A CORPORATION OF PENNSYLVANIA.

PROTECTIVE DEVICE.

1,194,228.

Specification of Letters Patent.

Patented Aug. 8, 1916.

Application filed June 21, 1912. Serial No. 705,004.

To all whom it may concern:

Be it known that I, ARTHUR PURDON, a citizen of the United States, and a resident of Wilkinsburg, in the county of Allegheny and State of Pennsylvania, have invented a new and useful Improvement in Protective Devices, of which the following is a specification.

My invention relates to protective devices for systems of electrical transmission and distribution, and it has special reference to such devices as are employed in connection with high-potential transmission systems at points where such systems cross over or span telephone lines, lighting circuits, highways, or steam and electric railway systems, for the purpose of preventing damage or personal injury in case of an accidental breakage of the high-tension conductor or conductors.

The object of my invention is to provide a protective device of the above-indicated character which shall be simple, durable and inexpensive in construction, quick, positive and reliable in operation, and be particularly adapted to instantaneously and concurrently release the respective ends of a spanning conductor in case the same becomes severed, whereby the possibility of subjecting underlying circuits, objects or persons to high potential is prevented.

According to my invention, I provide the adjacent poles of a high-tension transmission system, which are disposed on the respective sides of the area to be protected, with collapsible linkage mechanisms to support the respective ends of a conducting wire which is suspended between them and which spans the area to be protected, so long as said wire is intact. These mechanisms, however, are so constructed as to depend upon the tension of the spanning wire, and are adapted to collapse and release the respective ends thereof instantly and concurrently in case said wire becomes broken. Thus, the severed portions of the spanning wire are disconnected and segregated from the transmission system and hence can cause no damage or injury in case they come in contact with objects or persons.

My invention may best be understood by reference to the accompanying drawing in which—

Figure 1 is a view, partially in side elevation and partially in perspective, of a trans-

mission system embodying my invention which crosses over or spans a second system of distribution, such as telephone or telegraph lines or a low-voltage lighting circuit. Figs. 2, 3 and 4 are, respectively, 60 views in side elevation, in plan, and in end elevation, of a portion of the mechanism shown in Fig. 1, and Fig. 5 is a view in side elevation, showing a portion of said mechanism in its collapsed condition.

Referring to the drawings, a high-potential transmission line, embodying conductors 1, 2 and 3, crosses over a low-voltage distribution system 4, and is suitably supported on adjacent poles or supporting 70 structures 5 and 6 which are disposed at the respective sides of the low-voltage distribution system 4 or the area to be protected. The poles 5 and 6 are severally provided with suitable insulators 7 in accordance with 75 well known practice, and an upwardly projecting member 8 is secured in position by means of a supporting member 9 which is suitably clamped or otherwise secured to the insulator 7. The upright member 8 is provided with a parallel-motion linkage mechanism which comprises pivotally mounted arms 10 and 11 that are interconnected by means of a link 12. At the end of the lower and shorter arm 11, a forked retaining device 13 is pivotally mounted and comprises a main member 14 of curved cross section which is bent to elbow form to provide a normally vertical extension 15 having a longitudinal opening or slot 16 for a purpose to be hereinafter set forth. A member 17, also curved in cross section, is disposed at an angle to the extension 15 and is suitably secured thereto, while another member 18 is provided upon the opposite side of the 90 extension 15 and is inclined thereto and provided with laterally projecting arms 19. The upper and longer arm 10 is bent downwardly at its end and is provided with an inclined end portion 20 that is bifurcated 95 and is adapted, under normal conditions, to project beneath and engage the projecting arms 19 of the member 18.

Each end of the conducting wire 3, which spans the area to be protected, is provided 105 with a ball 3^a, or other suitable device, which is adapted to be retained in the forked device 13 between the parts 15 and 17 thereof. The portion of the conducting wire 3 adjacent to the end ball 3^a projects through the slot 16 110

and between the end portions 21 of the bifurcated member 20, said end portions 21 being widely separated to accommodate the ball 3^a. When the wire 3 is thus suspended 5 between the collapsible linkage mechanisms hereinbefore described, the tension thereof is sufficient to maintain the portions 19 of the retaining devices 13 in positive and intimate engagement with the bifurcated end 10 members 20 of the upper arms 10, whereby the collapse of the linkage mechanisms is prevented.

Secured to, and projecting upwardly from, the upper arm 10 is a member 22 which is provided with a series of holes or 15 apertures 23, and the conductors 1 and 2, forming parts of the high-tension transmission line, are secured to said member by any suitable means 24. It is evident that, 20 through the agency of the openings 23, the point of attachment of the conducting wires 1 and 2 may be adjusted as desired, whereby the force normally tending to rotate the linkage mechanism, hereinbefore described, 25 in an upward direction, may be varied and adjusted to any desired amount. The upper arm 10 projects slightly beyond the supporting member 8, and is provided with a projecting member or finger 25 which is 30 adapted to coöperate with a spring-supported stop 26 that is associated with the member 8. Flexible conducting shunts 27 are employed between the retaining members 13 and the line conductors 1 and 2.

Under normal operating conditions, and so long as the spanning wire 3 remains intact, the linkage mechanisms are restrained 35 from upward movement due to the action of the conducting wires 1 and 2, by reason of the tension of the spanning wire 3 which maintains the projecting arms 19 of the members 18 in engagement with the bifurcated end portions 21 of the upper arm 10. However, if the wire 3 becomes broken, or 40 otherwise severed, the tension thereof is relieved and the tendency of the linkage mechanisms to rotate upwardly is no longer opposed. Hence, the disengagement of the end portions 21 from the projecting arms 45 19 is effected, thereby allowing the retaining devices 13 to instantly drop or collapse into the condition indicated in Fig. 5. During this action, the balls 3^a at the ends of the spanning wire 3 are released from the 50 retaining devices 13, and the severed portions of said wire are thus concurrently disconnected from the high-tension system, thereby avoiding the possibility of subjecting any underlying low-voltage systems to 55 dangerous potentials. The spring supported stops 26 are adapted to be engaged by the fingers 25 during the upward movement of the linkage mechanisms, whereby sudden shocks to the mechanism and associated 60 conducting wires are prevented.

I have, for illustrative purposes, shown and described my invention as embodied in a single high-tension circuit, such, for instance, as a series arc lighting circuit, but those skilled in the art will readily understand that my invention is not restricted in this respect and is equally applicable to a plurality of conducting wires, such as are employed in polyphase systems of transmission. Furthermore, although I have set 70 forth my invention as embodying specific structural details and arrangement and location of parts, it is manifest that various modifications may be effected therein without departing from the spirit and scope of 75 my invention.

I claim as my invention:

1. In a protective device for connecting and disconnecting two portions of a transmission line conductor that are normally held in tension, the combination with a collapsible linkage mechanism, of a retaining member therefor pivotally secured to one link of the mechanism, an extension provided on another link for normally restraining said retaining member, means tending to disengage said retaining member and said extension, and additional means whereby a conductor-portion held in tension may neutralize the effect of said first means. 95

2. In a protective device for connecting and disconnecting two portions of a transmission line conductor that are normally held in tension, the combination with a parallel-motion linkage mechanism, of a retaining member secured to one link of said mechanism, an extension provided on another link thereof for normally engaging said retaining member, means tending to disengage said retaining member and said extension, and additional means effective only when transmitting the tension obtaining in one of the conductor-portions for neutralizing the effect of said first means. 100

3. In an apparatus for connecting and disconnecting two portions of a transmission line conductor one of which is normally held in tension, the combination with a linkage mechanism, and a retaining means therefor that normally holds said mechanism in operative position by reason of the force imparted thereto by the conductor-portion held in tension, of means for effecting disengagement between said retaining means and said mechanism when the tension in said conductor-portion is relaxed, thereby releasing one of the conductor-portions. 110

4. In a protective system for an electrical transmission line conductor mounted upon adjacent supporting structures in order to 125 provide a conductor-portion that is normally subjected to tension, the combination with a parallel-motion linkage device adapted to be mounted upon one of the supporting structures, and a retaining 130

member associated therewith, of means for restraining said retaining member in its set position, means tending to move said linkage device whereby said retaining member may be released, and an end member adapted to be connected to said tensioned conductor portion and engaging said retaining member to normally prevent movement of said linkage device by reason of the tension thereby imparted and to permit the movement thereof when the tension is released, whereby the said end member disengages from the said retaining member.

5. In a protective system for an electrical transmission line conductor mounted upon adjacent supporting structures, the combination with a parallel-motion device adapted to be mounted upon one of said supporting structures and comprising a plu-

rality of pivotally mounted parallel arms 20 and a connecting link, of a forked-retaining member pivotally associated with one of said arms and adapted to be engaged and restrained by the other arm under normal conditions, means tending to move said parallel-motion device to release said retaining member, and an end member associated with a portion of the transmission line conductor and normally supported upon said retaining means whereby movement of said parallel-motion device is prevented. 25 30

In testimony whereof, I have hereunto subscribed my name this 14th day of June, 1912.

ARTHUR PURDON.
